[57] **CLAIM**

The ornamental design for a headboard and footboard set for a bed, as shown and described.

DESCRIPTION

FIG. 1 is a perspective view of the headboard and footboard set, showing our new design;

FIG. 2 is a side elevational view of the headboard element of the set, the opposite elevational view being a mirror image thereof;

FIG. 3 is a front elevational view of the headboard element; FIG. 4 is an enlarged partial perspective view of the headboard element;

FIG. 5 is a perspective view of the footboard element of a the set;

FIG. 6 is a side elevational view of the footboard element, the opposite elevational view being a mirror image thereof; and,

FIG. 7 is a reduced, elevational view of the footboard element.

The rear of the headboard is unornamented.
